UNITED STATES PATENT OFFICE.

ROBERT M. TWEEDY, OF SPOKANE, WASHINGTON.

MINERAL SEPARATOR.

Application filed July 25, 1922. Serial No. 577,299.

To all whom it may concern:

Be it known that I, ROBERT M. TWEEDY, a citizen of the United States, residing at Spokane, in Spokane County and State of Washington, have invented certain new and useful Improvements in Mineral Separators, of which the following is a specification.

My present invention relates to improvements in mineral separators adapted especially for use in connection with the separation of gold bearing sand from the coarser gravel in placer mining operations, and for extracting the gold from the sand by means of washing and agitating the ore as it is passed through the machine embodying my invention.

The mineral separator as adapted for placer mining involves power driven mechanism whereby the ore is washed, the coarser materials separated out from the ore and disposed of, and then the fine material remaining, as sand, is treated to collect and extract the gold from the gold bearing sand.

The invention consists in certain novel combinations and arrangements of parts involving a washing trough and other features, compactly associated, and relatively disposed for co-operative action, as will be more specifically described hereinafter.

In the accompanying drawings I have illustrated one complete example of the physical embodiment of my invention in which the parts are combined and arranged according to the best mode I have thus far devised for the practical application of the principles of my invention.

Figure 1 is a view in side elevation of a separating mill embodying my invention.

Figure 2 is a top plan view.

Figure 3 is an end elevation at the charging or feeding end of the separator.

Figure 4 is an end elevation at the delivery or extracting end of the separator.

Figure 5 is a top plan view of the washing trough and washing blade therein.

Figure 6 is a sectional view of the extracting tank showing its relation to the washing trough.

In carrying out my invention I utilize the customary supporting frame structure 1, upon which is supported a feed hopper 2 into which the gold bearing material or ore is fed, after having been secured in the usual process of placer mining, or in any other customary manner. To facilitate the feed of the ore, the hopper is provided with

a transversely disposed shaft 3 having pins or prongs 3' thereon for beating, breaking, and feeding the material through the hopper. The shaft is revolved from a gear couple 4 through the gear shaft 5, disposed vertically at the side of the frame, and the gear shaft is revolved by a pair of bevel gears 6 from the power shaft 7, which extends longitudinally of the frame and is revolved from the driving pulley 7' by usual belt power.

The ore is passed from the inclined hopper 2 into the open end of a rotary, reticulated drum or sieve 8, supported in inclined position, by rollers 8' at the top of the frame, to receive the ore. The centrally disposed shaft 9 of the rotary drum is operated from the power shaft by sprocket chain 10 and sprocket wheels 10' and 10^a at the discharge end of the separator, and by these connections the drum is revolved or rotated. The coarse or heavy material, as gravel, is shaken and agitated within the drum, and passes from end to end thereof, and is disposed of at the lower end of the drum by falling into the trough 24, located beneath the outlet end of the drum.

Water is supplied to the ore within the rotary drum from the water supply pipe 11, which terminates in a nozzle 12 located in and disposed longitudinally of the drum, for dissolving the lumps of material and facilitating separation thereof. The water sprayed or sprinkled in the interior of the drum, falls by gravity through the lower parts of the separator to insure a supply throughout the different steps of the operation of the separator.

Below the rotary drum is located a longitudinally disposed shaking screen or agitator, comprising three oscillating flights as 13, 14 and 15, the upper and lower screens being arranged in parallelism and inclined, and the intermediate screen 14 being inclined in opposite direction, or located at an angle to the upper and lower screens. The screens may be of various sizes or mesh, capable of permitting passage therethrough of the gold bearing sand as it falls from the drum 8 to the agitator beneath the drum, and such materials that are too large or too coarse to pass through the mesh of the lower screen 15, are disposed of through the discharge end 25 of the lower screen.

To permit oscillation of the agitator, it is suspended from a suitable member of the

frame by two pairs of pivoted links 16, supported from the frame and connected to the agitator to permit the latter to swing or oscillate longitudinally of the frame. The 5 oscillating movement is imparted to the agitator through a crank shaft 17, journaled transversely of the frame at the feed end or charging end thereof, and revolved by gears 18, one of which has a sprocket for the main 10 sprocket chain 19. The chain 19 is driven by the main sprocket 20 on the power shaft, and is guided in a triangular path, transversely of the frame, under the upper guide wheel 21 and around a sprocket wheel 22 15 on the countershaft 22'. The countershaft 22' revolves the crank shaft through the gears 18, and the crank shaft is connected to the agitator by the pivoted pitman 23, for pushing and pulling the agitator and 20 swinging it in its suspended links.

The finest of the gold bearing sand passes through the lower screen 15, the coarser particles, after passing over or through the upper screen and the intermediate screen to 25 the lower screen, being disposed of and discharged by action of the agitator, out of the discharge end 25 of the agitator.

From the agitator the finely separated material falls by gravity into a washing trough 30 26, disposed below the agitator, and also inclined in the general direction and parallel with the drum and agitator, and in which trough the falling water is caught and passed to its lower end. Within the washer 35 trough is disposed a flat, washing blade 27 having serrated or toothed edges 27' and a number of perforations or holes 28 there-through to permit passage of the water as this blade is revolved for stirring the watered sand. The blade is fixed to a longitudinally extending shaft 29 journaled in the ends of the washer trough, and the shaft 40 has a driven sprocket wheel 30 to receive motion from the power shaft 7 through the 45 main drive sprocket chain 19, and by means of which the shaft and its blade are revolved. By the action of the serrated edges of the blade and the perforations in the blade the water and gold bearing sand are stirred in 50 order to secure a final washing and separation of the sand from the gold particles, and the separated, and washed material finds its way down the inclined trough 26 to its discharge end 31.

The discharge end 31 of the washer trough is connected with an extractor trough or tank 32 at the upper end of a transversely disposed and inclined extractor tank 33 at the discharge end of the separator. The inclined bottom of this tank is fashioned with a stepped formation to provide concaved portions or pockets 34 arranged in spaced series, one below another and extending 60 transversely of the extractor tank. These 65 pockets are supplied with mercury, which

has an affinity for the particles of gold carried by the wet sand, and the gold particles are gathered in the pockets while the sand finds its way to the lower end of the tank and out at the end 35. While traveling down 70 the inclined bottom of the extractor tank, the movement of the material is assisted by mechanism actuated from the sprocket wheel 36 on the shaft 29 of the washer. This auxiliary driving sprocket 36 drives the chain 75 37 which passes over a series of sprockets 38 located exteriorly of the extractor tank on the ends of shafts 39, each shaft being journaled in the walls of the extractor tank and located just above a pocket 34. Each 80 shaft 39 has a fixed blade 40, similar to the serrated and perforated blade 27 of the washer, and the respective blades and shafts are revolved counter clockwise, with the edges of the blades passing over the mercury 85 in the pockets. It will be apparent that by the action of the revolving blades 40 as they pass over the mercury pockets the gold particles are separated from the sand by the serrated edges of the blades in order that 90 the gold may be gathered in the pockets, and the sand or lighter material is passed toward the discharge end of the tank.

To insure proper passage of the material and hold the mass at the bottom of the tank, 95 a series of transversely disposed, spaced, and adjustable baffle boards 41 are used. These baffle boards project downwardly into the tank toward its bottom and are supported in guide grooves 42 in the side walls of the 100 tank, in order that they may be elevated or lowered for the purpose of maintaining the moving mass on the bottom of the tank.

When the gold reaches the extractor, it will be evident that it has been properly 105 prepared for the action of the mercury in which it is retained, and from which it may subsequently be gathered in usual manner.

The separator as thus described and illustrated is compactly arranged in order 110 that the gold bearing ore may be fed to the charging hopper, and the material then passes through the successive steps, without necessity for transfer or handling, except in the mill, until the extracted gold is collected 115 in the pockets of the extractor.

Having thus fully described my invention, what I claim as new and desire to secure by Letters Patent is:—

The combination in a mineral separator 120 with a washing trough adapted to receive wet material, of a shaft journaled in said trough, a straight flat blade fixed at opposite sides to said shaft having straight serrated edges and perforations in its body, means for revolving said shaft and blade, and a tank 125 adapted to receive the washed material from said trough.

In testimony whereof I affix my signature.
ROBERT M. TWEEDY.
